UNITED STATES PATENT OFFICE

109,818

DESIGN FOR A DISPLAY CABINET

Charles F. Simms, Concord, N. H., assignor to
Concord Silversmiths Corporation, Concord,
N. H., a corporation of New Hampshire

Application December 30, 1937, Serial No. 73,963

Term of patent 3½ years

To all whom it may concern:

Be it known that I, Charles F. Simms, a citizen of the United States, residing at Concord, in the county of Merrimack and State of New Hampshire, have invented a new, original, and ornamental Design for a Display Cabinet, of which the following is a specification, reference being had to the accompanying drawing, forming a part thereof.

Figure 1 is a front perspective view of the display cabinet showing my new design.

Figure 2 is a side elevational view of the same on a reduced scale.

Figure 3 is a plan view of the same on a still further reduced scale.

The rear of the cabinet is plain.

I claim:

The ornamental design for a display cabinet as shown and described.

CHARLES F. SIMMS.
